Patented June 6, 1922.

BY

ATTORNEY.

UNITED STATES PATENT OFFICE.

FRANK G. VAN DYKE, OF DETROIT, MICHIGAN.

ELECTRIC HEATER.

1,418,496.

Specification of Letters Patent. Patented June 6, 1922.

Application filed November 15, 1920. Serial No. 424,102.

To all whom it may concern:

Be it known that I, FRANK G. VAN DYKE, a citizen of the United States, and residing at Detroit, in the county of Wayne and State 5 of Michigan, have invented a new and Improved Electric Heater, of which the following is a specification.

This invention relates to a flexible ribbon-like electric heater which may be attached 10 to cups, bowls, tubes, and to tubular and spherical bodies generally, and its object is to provide a heating device of this character which may be readily bent to conform to the body to be heated, which will have com- 15 paratively great heating capacity, and which may be readily adjusted to bodies of different dimensions.

This invention consists in the details of construction illustrated in the accompanying 20 drawings and particularly pointed out in the claims.

In the drawing, Fig. 1 is an elevation of an intake manifold of an internal combustion engine and a carburetor attached thereto, and heating devices secured to the carburetor float chamber and carbureting chamber and to the shank of the intake manifold. Fig. 2 is an outside elevation of this improved heater. Fig. 3 is an inside elevation 30 of one end thereof. Fig. 4 is a section on the line 4-4 of Fig. 2. Fig. 5 is a section on the line 5-5 of Fig. 3. Fig. 6 is a section on the line 6-6 of Fig. 5. Fig. 7 is an elevation of one end of the heating element. Fig. 8 is a plan on a smaller scale of the 35 heater when bent to cylindrical form.

Similar reference characters refer to like parts throughout the several views.

This electric heater embodies a flat heating element, preferably the element 1 shown 40 in Fig. 7, which has a plurality of strands 2 united by the ends 3 which are formed with the holes 4 to receive the stems of the binding posts 5. On the outside of this element 45 is the strip 6 of insulation, preferably mica, which receives the heads of the posts 5, and outside of the strip 6 is an imperforate second strip 7.

Back of the heating element is a strip 8 50 of insulation, which may be mica or asbestos, and enclosing the heating element and the insulations is a shell formed of a strip of sheet metal comprising a back 9 and bent-over side edges 10. At the ends of the shell 55 the side edges are in the form of ears 12

and the ends of the back are bent forward to form the hooks 13.

On the ends of the posts 5 are nuts 14 and the connector wires are secured between these nuts and the metal washers 15 (see 60 Fig. 4). Insulating washers 16 separate the posts from the back 9 of the heater shell, which is cut out at 17 so as not to touch the screws which are held from moving out of place by the inner mica strip 6. 65

Fasteners 18 in the form of metal ribbons are attached to the ends of the heater and have slots 19 to receive the hooks 13, the outer edges 20 of the cross bars between the slots being preferably tipped slightly so as 70 to insure proper engagement with the hooks 13. The ears 12 at the ends of the edges 10 are bent down when the fasteners have been positioned to prevent displacement. At their outer ends these fasteners are 75 preferably formed with stiffening flanges 22 and holes 23 to receive the bolt 24 by means of which the heater may be secured to the body 21 to be heated.

In Fig. 1 I have shown a grounded battery 25 connected to a switch 26 and wires 27, 28 and 29 connecting to heaters A, B and C mounted on the neck of the intake manifold 30, on the carbureting chamber 31 of a carburetor and on the bowl 32 thereof 80 respectively. Wires 33, 34 and 35 respectively connect these heaters to a bolt 36 to ground the circuits. It will be understood that any one or two of these heaters may be omitted and that they may be employed 85 wherever else such devices may be required.

The details and proportions of the various parts may be varied by those skilled in the art without departing from the spirit of my invention as set forth in the following 90 claims.

I claim:—

1. An electric heater comprising a sheet metal strip having its edges folded over, two strips of insulation and a heating element between them held in position by the edges of the strip, adjustable fastening devices at the ends of the metal strip and having holes in their ends, a bolt passing through said holes to draw the heater around 105 the article to be heated, said heating element comprising flat parallel strands and ends connected integrally to the strips, and binding posts extending from the ends of the heating element. 110

2. An electric heater comprising a sheet metal strip having its edges bent over, strips of insulation and a heating element between the insulations held in position by said edges, the ends of the metal strip being formed with hooks, fastening devices in the form of metal ribbons formed with transverse slots and extending between the sheet metal strip and its bent-over edges, the hooks at the ends of the strip extending into said slots, and means to connect the ends of said fasteners.
3. An electric heater comprising a sheet metal strip having its edges bent over, strips of insulation and a heating element between the insulations held in position by said edges, the ends of the metal strip being formed with hooks, fastening devices in the form of metal ribbons formed with transverse slots and extending between the sheet metal strip and its bent-over edges, the hooks at the ends of the strip extending into said slots, means to connect the ends of said fasteners comprising a bolt extending through holes in the outer ends of the fasteners, the edges of the ends of the fasteners being bent up to stiffen such ends.

FRANK G. VAN DYKE.
